CLAIM

The ornamental design for a multiple remote control holder for hook and loop equipped remote control devices, as shown and described.

DESCRIPTION

FIG. 1 is a top, front, and left side perspective view of my new remote control holder;

FIG. 2 is a top plan view;

FIG. 3 is a bottom plan view;

FIG. 4 is a front elevational view; the rear being a mirror image thereof;

FIG. 5 is a top plan view, showing the orientation of remote control devices to the holder;

FIG. 6 is a left side elevational view, the right side being a mirror image thereof; and,

FIG. 7 is a section view, taken along section lines 7—7 in FIG. 5.

The remote control devices depicted in phantom lines in FIGS. 5 and 7 are for illustrative purposes only and form no part of the claimed design.

My remote control holder is characterized by a pedestal base, a felt covered mounting surface for hook and loop equipped remote control devices, and protective end handles at both sides of the remote control mounting surface.
